ELEVATOR

Joseph R. Jackson, Jr., Boston, Mass.

Application April 5, 1928, Serial No. 267,716

9 Claims. (Cl. 187—29)

The invention to be hereinafter described relates to electric elevator systems.

Many operators of elevator cars fail to make stops level with floors within reasonable time, do 5 not always stop at floors in response to calls to floors, do not always stop at floors to leave passengers desiring to leave cars at particular floors, and in the case of a bank of cars, do not always signal to other cars in the bank that their cars 10 are full and running as express cars. The system of the present invention provides automatic means which relieves the operator of the car of a number of operations which he has heretofore been called upon to perform, and eliminates the 15 faults above referred to.

Another purpose of the invention is to provide a supplemental system which may be readily applied to existing elevator systems without material alteration thereof, and without interference with the ordinary operation of the elevator. This supplemental system may be applied to ordinary electric elevator systems irrespective of 20 their type of control. It is applicable to elevators of the rheostatic type or the variable voltage 25 type, which are well known types of electric elevator installations.

Another purpose of the invention is to provide an improved push button electric elevator system in which a car will automatically be 30 brought to rest at a floor when a person at a floor presses a button. The construction is such that an up or down travelling car can be stopped at any floor by a person at that floor without depending on stopping of the car by the operator 35 in response to the call.

Another purpose of the invention is to provide automatic sequence of operations. The system is such that the operator of the car on receiving passengers can pre-set the system to make stops 40 at floors, and the car automatically will make those stops without further attention on the part of the operator. Also the system is such that in the case of buttons at several different floors pressed concurrently or nearly so to summon a 45 car to said floors, the car automatically will respond to the calls to those floors in sequence. In installations having a bank of cars, the system provides for further sequence of operations. The interrelation of the control systems for the cars 50 of the bank is such that when a button is pressed at a floor to pre-set the system to cause a car to stop at that floor, the car of the bank which is nearest to and within practicable stopping distance, will make the stop at that floor, and the 55 other cars of the bank will not make the stop.

If one of these cars has to stop to leave passengers, it will make the stop and the other cars will continue on. If a car is approaching a floor in the given direction, the operator of that car can set the system by use of a button in the car so that the car will stop at the floor and all other cars travelling in the same direction within a distance not greater than the distance between two adjacent floors, even though travelling in advance of the car to stop at the floor, will not be responsive to summoning a car to the floor by pressing a button at that floor. 60

Another purpose is to provide an elevator system for a bank of cars in which when a button is pressed to summon a car to a floor and the car 70 approaching the floor is too near it properly to decelerate to a stop, the next car in the bank going in the same direction will automatically make the stop at that floor without additional pressing of the floor button. Also, the operator in the car 75 cannot cause the car to make a stop unless it is far enough from the floor properly to make that stop, except in emergency cases.

Another purpose of the invention is to provide means operable in response to the speed of the 80 car, automatically to initiate the first step of deceleration of the car in approaching a floor, at a greater distance from the floor when the car is running as an express or at full speed, than when the car has not had time to build up to full 85 speed as happens when a car starts from a floor and makes a stop at the next adjacent floor.

Another purpose is to provide means for varying the time required for the car to decelerate to a stop at a floor taking into account the resultant force urging the car toward the floor, due to the weight of the car, the varying load thereon, the counterweight and gravity effect. Deceleration should commence at a greater distance from a floor with resultant heavier loads than with 95 lighter loads. This is accomplished, in the present instance by means which is pre-set in response to operation of the weighing machine in the car. 90

Another purpose is the provision of means automatically to prevent a fully loaded car from stopping at floors in response to pressure of floor buttons. To accomplish this, in the present instance, the car is provided with a weighing machine for weighing the load in the car, and means is automatically operated by the weighing machine to cut out the automatic floor push button control for that car so long as it is fully loaded. Under this condition the car will stop under 105 the control of the operator. 110

Another purpose is to enable the car to run as an express car under the control of the operator and not respond to push button calls to floors.

Still another purpose of the invention is to provide a supplemental system for ordinary elevator systems which is simple considering the number of things which it accomplishes.

With the aforesaid and other purposes in view, the character of the invention may be best understood by reference to the following description of an embodiment thereof shown in the accompanying drawings, wherein:

Fig. 1 is a vertical section through an elevator system embodying the invention;

Fig. 2 is a horizontal section through the base of the elevator car, parts being broken away to show the weighing machine suspension mechanism in the base;

Fig. 3 is a vertical transverse section through the car base;

Fig. 4 is a vertical longitudinal section through the car base;

Fig. 4a is an elevation showing the arrangement of the push buttons in the cars;

Fig. 5 is a side elevation of the positioning machine, the supplementary control board, the selector, the adjustable decelerating contact carrying panel, and the electric motor for the positioning machine and panel;

Fig. 6 is a sectional detail of one of the selector brushes;

Fig. 7 is a vertical section through the selector;

Figs. 8, 9 and 10 show the wiring diagram and instrumentalities associated therewith of the attachment for cooperation with the usual main control board of an electric elevator system; and

Fig. 11 is a diagram showing control systems for a bank of cars embodying the invention in a cooperative relation.

Referring to the drawings, the elevator system shown therein as embodying the invention comprises the car 1 in the hatchway 2 suspended by cables 3 which pass around the drum 4 in the penthouse 5 and pass thence downward in the hatchway to the counterweight 6. The drum is driven by an electric motor 7 provided with the usual brake which is unnecessary to show herein.

The elevator car (Figs. 2, 3 and 4) contains a shallow chamber 8 in which is mounted a weighing machine comprising a platform 9 which serves as the car floor. Projecting down from the platform are wedge-shaped lugs 10 resting on similarly-shaped seats in yokes 11 and 12 of the weighing machine suspension. These yokes have ends pivotally mounted on bearings 13. The yoke 11 has an arm 14 overlying an arm 15 of the yoke 12, said arms being connected by a ring 16. A coil spring 17 is interposed between the bottom of the base and the arm of the yoke 11, tends to rock the yokes upward, and is adapted to yield when a load is placed on the platform. The arm 14 is longer than the arm 15, and has a seat in the under side thereof engaged by a finger 18 on a rock shaft 19 projecting out beyond one side of the car.

To prevent dirt from reaching and interfering with proper operation of the weighing machine suspension mechanism, strips 20 of rubber or other material are fitted into opposed grooves in the base and in the edges of the platform. To assist in ventilating the car, the portion of the base surrounding the platform may have a series of ports 21 therein communicating with a deflecting hood 22.

This weighing machine is disclosed in my co-pending application Serial No. 233,119, filed November 14, 1927, to which reference may be had for details of its construction.

This weighing machine will operate in response to the load on the platform to rock the shaft 19, and the motion thus produced may be utilized for regulating certain instrumentalities of the elevator system. In the present instance this machine operates a selector S (Figs. 1, 5, 6 and 7) mounted on the car and comprising a stationary ring 23 of insulation material and carrying a series of spring-pressed brushes 24. Within the ring and engaged by the brushes is a disk or rotor 25 of conductive material excepting an insulation spot 26. This rotor is on a shaft 27 having a pinion 28 thereon meshing with a toothed sector 29 on a stud shaft 30. Connected to this stud shaft are a pair of arms 31 connected in turn to links 32 on arms 33 on the rock shaft 19 referred to. The construction is such that when a load is placed on the platform the rotor will be turned and cause the insulation spot thereof to move to a position at the end of one of the brushes.

The selector controls a positioning machine H (Fig. 5) comprising a conductive bar 34, a row of contact segments 34a insulated from one another, and a bridge contact 34d on a carrier B having a hub 35 threaded on a screw shaft 36 rotated by an electric motor 37. A brake 38 is provided for this screw shaft, and comprises a drum 39 on the shaft and a shoe 40 applied by a coil spring 41 and released by an electromagnet 42.

The selector S has an arm 43 on a hub 43a on an insulation sleeve 44 on the rotor shaft, said arm carrying a pair of contacts 45 and 46 respectively for engagement with fixed contacts 47 and 48 on the selector ring. The rotor will be turned by the weighing machine through the means described in a clockwise or a contra-clockwise direction depending on whether the load on the platform increases or decreases. The arm hub has sufficient frictional engagement with the insulation sleeve so that on initial turning of the rotor the arm will be moved in the direction of turning of the rotor, and thereby cause one of the contacts on the arm to engage one of the fixed contacts on the ring, but this will not interfere with continued turning of the rotor. These contacts controlled by the arm are in circuits to be described for the positioning machine motor, and control the direction of rotation of said motor and the direction of travel of the bridge contact carrier.

Contacts 49 and 51 are carried by a lever 51a pivotally mounted on the ring, and contacts 50 and 52 are carried by a bracket 49a on the selector ring. A coil spring 53 connected to the ring and lever tends to hold contacts 49 and 50 in engagement with each other, and contacts 51 and 52 in engagement with each other. A pin 54 on the rotor is adapted to engage the lever and disengage said contacts. These contacts are in circuits to be described which are automatically interrupted to prevent a fully loaded car from responding to a call by a prospective passenger pressing a button at a floor.

The circuit for rotating the position machine motor in one direction is traced through line wire 55 (Fig. 5), the selector rotor and all of the brushes of the selector ring excepting the one engaging the rotor insulation spot. The circuit is traced thence through wires in cable 56 to the row of contact segments 34a, bridge contact 34d on carrier B, bar 34, limit switch 57, wire 58, 150

limit switch 59, wire 60, position machine brake coil 61, wire 62 to one of the brushes of the position machine motor, through its commutator and other brush, wire 63, field coil 64, wire 65, contacts 5 47 and 45 at selector, and line wire 55.

The circuit for rotating the position machine motor in the opposite direction is traced through line wire 55, the selector rotor and all the brushes of the selector ring excepting the one engaging the rotor insulation spot. The circuit is traced thence through wires in cable 56 to the row of contacts 34a of the position machine, bridge contact 34b on carrier B, limit switch 57, wire 58, limit switch 59, wire 60, brake coil 61, wire 62, one of the brushes of position machine motor, through its commutator and other brush, wire 63, field coil 66, wire 68, contacts 48 and 46 at selector, and line wire 55.

The field coils 64 and 66 of the motor are wound in opposite directions and therefore, when the circuit including one of these coils is completed, the motor will be rotated in one direction, and when the circuit including the other coil is completed, the motor will be rotated in the opposite direction.

Since the motor and the coil of the magnet for releasing the brake for the motor driven shaft are in series when the motor circuit is broken, the brake magnet will be de-energized and the spring of the brake will apply the latter promptly to arrest rotation of the motor shaft and travel of the bridge contact carrier B.

The wires conducting the current to the position machine motor will cause the motor to rotate until the bridge contact carrier arrives at the contact segment of the row of contact segments 34a connected to the wire in cable 56 which leads to the selector brush opposite the insulation spot of the rotor. When the bridge contact reaches this segment which does not carry current, the motor will be arrested and promptly brought to a stop by the brake.

As stated, one of the purposes of the invention is to provide means for varying deceleration of the car to a floor which is accomplished by means which is pre-set in response to operation of the weighing machine in the car. This machine operates through the selector, the position machine and motor to control the starting, stopping and direction of rotation of the motor. In the circuits to be described for the elevator are sets of graded contacts which are mounted on a panel 67 (Fig. 5) adjacent a contact carrying board 68. At the opposite ends of the panel 67 are elongated slots 69 receiving pins 70, and fast on one end of the slide is a nut 71 in which a screw shaft 72 is threaded. Fast on said shaft is a gear 73 meshing with a pin 74 on a stud shaft carrying a gear 75 meshing with a pinion 76 on the motor shaft. These gears provide a reduction train between the motor shaft and the screw shaft 72. The construction is such that the motor will be rotated in one direction or the other depending on increase or decrease in the load on the car, and the panel 67 will receive a slight adjustment toward the right or toward the left. The effect of this adjustment in respect to variation of deceleration of the car to a floor will hereinafter be made clear.

Having described certain of the instrumentalities employed in connection with the system, next will be described the wiring diagram and control devices cooperating therewith for the control of the elevator cars, more particular reference being had to Figs. 8, 9 and 10.

The system of the present invention is applicable to make or break circuits of a standard elevator control board formerly operated by a switch in the elevator car manually controlled by the operator in the car. The hand switches in the three cars of the bank are designated C' C₂ and C³, in Fig. 11. The lines leading from this control board to the present system comprise in the diagram feed line L, up direction wire U', down direction wire D', second speed wire S', and third speed wire S².

In the present instance for purposes of illustration a bank of three elevators is considered, but any number may be employed as required. The main control boards for these three elevators are designated M', M² and M³ in Fig. 11. Since the construction and operation of these boards are well understood in the art, it is not necessary to show and describe them in detail herein. They are in circuits including main positive line 77, branch lines 78 and main negative line 79 and branch lines 80.

Since the apparatus of the present invention is applicable to the system for each of the three elevators, in general, description of one will suffice for all, coupled with adequate exposition of the relation and control of the elevators of the bank.

Referring now to Figs. 8, 9 and 10, and assuming the car is to travel down, the operator in the car presses a down button 101 in the car to complete a circuit which energizes a magnet 103. This circuit is traced through line wire 105, stop button 107, wire 109, down button 101, wire 111, switch 113, contact 115, wire 117, contact 119, switch 121, contact 123, wire 125, magnet 103, wire 127 and line wire 129. Energization of the magnet 103 moves the switch 131 into engagement with contacts 133, 135, 137 and 139 which are in circuits similar to those made by the three speed car switch of the usual system. In the ordinary system, if the switch engaged two of these contacts, one speed would be obtained, if it engaged three contacts, another speed would be obtained, and if it engaged four contacts, a third speed would be obtained. In the present system the different speeds are not obtained in this way. Closing of the switch 131 completes circuits for full speed of the car. The reason for this is that deceleration is controlled automatically by means to be described.

Since the down button 101 is pressed momentarily, magnet 103 is made a holding magnet by a shunt around said button including wires 217 and 140, contact 140a, switch 421, contact 140b, wire 140c leading to wire 111.

The circuit which is interrupted by pressing a button at the first floor is traced through main line 141, wire 143, contact 145, push button 147, contact 149, wire 151, contact 153, switch 155, contact 157, wire 159, wire 161, magnet 163, wire 165 to main line 167. Breaking this circuit de-energizes the magnet 163 and allows the switch 155 to open under the influence of gravity. As the car approaches the floor, a bridge contact carrier 169 is caused by travel of the car to reach contact 171.

This carrier is caused to travel by a screw shaft 81 (Fig. 5) journalled in bearings on the board 68, referred to. Fast on one end of the shaft is a worm gear 82 meshing with a worm 83 on a shaft 84 carrying a grooved toothed wheel 85 connected by a perforated tape 86 with the elevator car (Fig. 1), the tape being maintained taut by a weighted pulley 87. As the car travels in the

hatchway, the tape rotates the wheel 85 and bridge contact 257 leaves contact 261, it interrupts another of said circuits, and when the bridge contact 257 leaves the contact 263, it interrupts the final circuit in the deceleration control, and the car is thus brought automatically to rest at 80 the floor.

The carrier 169 carries a contact 173 which will engage the contact 171 completing a circuit for the down magnet 177 traced through main line 141, wire 179, wire 181, wire 183, contact 185, switch 187, contact 189, wire 191, contact 171, contact 173 on carrier 169, wire 193, contacts 51 and 52 at selector, wire 193a, switch E, wire 193b, wire 197, magnet 177, wire 199, contact 201, switch 203, contact 205, wire 207, wire 209, wire 217, wire 109, stop button 107 in car, and line wire 105.

Magnet 177 is now energized, and it moves the switch carrier 219 which has thereon switches 221, 223, 225, 227, 229, 231, all of said switches being insulated from one another. The switches 225, 227, 229 and 231 are brought into engagement with contacts 233, 235, 237 and 239 which have current standing thereon through wires 241, 243, 245 and 247 which respectively lead to contacts 133, 135, 137 and 139 referred to, and engaged by switch 131.

When the switch carrier 219 is moved by the magnet 177 as described, it moves switch 113 referred to, out of engagement with contact 155, and this breaks the circuit to the down magnet 103. The car continues to travel through the circuits which include switches 225, 227, 229 and 231, which are respectively in engagement with contacts 233, 235, 237 and 239. The circuit described for energizing the deceleration control magnet 177 was completed by engagement of the contact 173 on carrier 169 with contact 171. This condition is for but a moment, and the magnet 177 now becomes a holding magnet through a circuit which is traced through main line 141, wire 179, wire 249, contact 251, switch 221 on carrier 219, wire 253, contact 255, bridge contact 193 on carrier 169, bar 195, wire 197, magnet 177, wire 199, contact 201, switch 203, contact 205, wires 207 and 209, wires 217 and 109, button 107 and line wire 105.

Next will be described the means for causing deceleration of a car in coming to its stop. As the car approaches the floor the carrier 169 after causing contact 173 to leave contact 171, will bring a bridge contact 257 on carrier 169 into engagement with three contacts 259, 261 and 263 and a bar 265, said contacts being of different lengths. A set of contacts 267, 269 and 271 is provided for another floor, and a set of contacts 273, 275 and 277 is provided for still another floor. A set of such contacts will be provided for every floor, three sets being shown herein for three floors for purposes of illustration and all of said sets being mounted on the panel 67, referred to. The bridge contact 257 on carrier 169 cooperates with all of these sets of contacts and bar 265.

The bar 265 is connected by wire 279 with switch 225 on carrier 219. The contact 263 is connected by wire 281 with switch 227. The contact 261 is connected by wire 283 with switch 229. The contact 259 is connected by wire 225 with switch 231.

As the car approaches its stop, the bridge contact 257 on carrier 169 will be brought into engagement with contacts 259, 261 and 263. The bridge contact will move along said contacts and leave them in the order named. When the bridge contact 257 leaves contact 259, it interrupts one 75 of the circuits for the three speeds. When the

bridge contact 257 leaves contact 261, it interrupts another of said circuits, and when the bridge contact 257 leaves the contact 263, it interrupts the final circuit in the deceleration control, and the car is thus brought automatically to rest at 80 the floor.

When the car starts from the floor and is to make a stop at the next adjacent floor, although the car switch is thrust to full speed position, there is not time for the motor to build up to full speed. On the other hand, when the car starts from a floor and is to make a stop at the second or other floor beyond, or when the car is running as an express, when the car switch is thrust to full speed position, the motor has time to build up to full speed. When the car is traveling at express speed, the first step of deceleration should be initiated when the car is further from the floor than when the car is traveling at local speed. Accordingly, means is provided operable in response to the speed of the car, automatically to initiate the first step of deceleration at a greater distance from a floor when the car is running as an express than when the car is running at lower speeds. This means includes a governor 286 (Figs. 5 and 100 10) which may be located in the penthouse and may be rotated by the toothed wheel 85 which is driven by the perforated tape 86 connected to the elevator car. To this end the worm shaft 84 has a bevel gear 286a thereon meshing with a 105 bevel pinion 286b fast on the governor shaft. The governor has a link 286c connected to a lever 286d pivotally mounted intermediate its ends and having a contact 286e at the outer end thereof. The governor has a link 286f connected to a lever 285g 110 pivoted intermediate its ends and carrying a contact 286h at the outer end thereof.

Adjacent the contact 286e are a pair of contacts 286i and 286j. The contact 286i is connected to a wire 273, and a branch wire 273a leads therefrom to a contact 273b adjacent the end of the contact 273 referred to. The contact 286j is connected to a wire 274, and a branch wire 274a leads therefrom to a contact 274b adjacent the contact 273b. A wire 276 tapped from wire 285 120 leads to the governor actuated contact 286e. Branch wires 276a and 276b lead from wire 276 to contacts 267 and 273, respectively.

The construction is such that at low speed the governor actuated contact 286e will engage both 125 of the contacts 286i and 286j, and the bridge contact 257 on carrier 169 will not initiate the first step of deceleration until said contact has left contact 274b. When the car is running as an express, the governor will have moved the contact 130 286e out of engagement with the contacts 286i and 286j, thereby interrupting the circuits including the contacts 273b and 274b and the first stage of deceleration will be initiated earlier, that is, when the bridge contact 257 leaves the contact 273 135 and the car is at a greater distance from the floor.

When the car is running as an express the circuits including both of the contacts 273b and 274b will be broken, but when the car is running at a slower speed, the circuit including the contact 140 273b will not be broken and deceleration will be initiated when the car is nearer the floor. And when the car is running at a still slower speed, the circuits including both of the contacts 273b and 274b will be closed and deceleration will be initiated when the car is still nearer the floor.

The deceleration control has been described in respect to one of the floors, but it will be understood it is the same for all floors.

While for purposes of illustration two contacts 150

have been shown adjacent each of contacts 259, 267 and 273 in circuits controlled by the governor for varying the distance from the floor in initiating deceleration to stop, it will be understood 5 that any number of such contacts in circuits controlled by the governor may be employed depending upon the high speed of the car.

The circuit for the down magnet 103 includes the switch 121 and contacts 119 and 123, the arrangement being such that this circuit is broken 10 on energization of the up direction magnet 409 to be referred to. Similarly, the up direction magnet cannot be energized when the down-travel magnet is energized, as will be hereinafter described.

Next will be described the circuit controlled by the button at the second floor for bringing a car to a stop at that floor. This circuit includes wire 287 tapped off of line wire 141, contact 289, second floor push button 291, contact 293, wire 295, contact 297, switch 299, contact 301, wires 303, 20 305, magnet 307, wire 309, wire 165 and line wire 167.

Before the second floor button 291 is pressed, the magnet 307 is in energized condition, and the 25 switch 299 is closed. When this button is pressed the circuit to the magnet is broken and the switch 299 opens under the influence of gravity. This initiates the operations already described for bringing the car to a stop at the second floor. The 30 circuit for accomplishing this is traced through main wire 141, wire 179, wire 181, wire 311, contact 313, switch 315, contact 317, wire 319, contact 321, contact 173, wire 193, contacts 51 and 52 at selector, wire 193a, switch E, wire 193b, wire 35 197, magnet 177, wire 199, contact 201, switch 203, contact 205, wires 207, 209 and 217, stop button 107 and line wire 105.

Next will be described the circuit for stopping the down travelling car at the third floor. The 40 circuit is traced through a wire 323 tapped from line wire 141, contact 325, third floor push button 327, contact 329, wire 331, contact 333, switch 335, contact 337, wire 339, wire 341, magnet 343, wire 345, and line wire 167. Before the third floor 45 push button is pressed the circuit is completed and the magnet 343 is in energized condition, and the switch 335 is closed. When the button is pressed the circuit is broken, the magnet is de-energized and the switch 335 opens under the influence of gravity. On opening of the switch 50 335 a circuit is completed which is traced through line wire 141, wire 179, wire 181, wire 347, contact 349, switch 351, contact 353, wire 355, contact 357, contact 173, wire 193, contacts 51 and 55 52 at selector, wire 193a, switch E, wire 193b, wire 197, magnet 177, wire 199, contact 201, switch 203, contact 205, wires 207, 209, 217 and 109, stop button 107, and line wire 105.

Means is provided for completing the circuits 60 for the floor magnets, and energizing said magnets so as to close the switches which were opened by pressing the floor buttons. This is done so that after a floor button has been pressed to bring the car to a stop, any additional pressing of floor 65 buttons will not deenergize said magnets, and other cars of a bank of cars will be prevented from responding to that call. Also this means re-sets the switches so as to be ready to stop cars for calls after the car has left the floor to which it was 70 called. Said means for the first floor magnet includes a circuit traced through line wire 141, wire 179, wire 180, contact 359, switch 223 on carrier 219, wire 361, bar 363, bridge contact 365, contact 367, wire 369, wire 161, magnet 163, wire 165 and line wire 167. When this circuit is completed by

engagement of bridge contact 365, with bar 363 and contact 367, the first floor magnet 163 is energized, and the switch 155 is closed, thereby completing the circuit through push button 147 as well as through the circuit just described, so that the magnet 163 becomes a holding magnet, and starting of the car and movement of the bridge contact 365 away from contact 367 leaves the magnet in energized condition and through the floor button circuit only.

To energize the second floor magnet 307 independently of the push button circuit and close the switch 299, a circuit is provided traced through line wire 141, wire 179, wire 180, contact 339, switch 223, wire 361, bar 363, bridge contact 365, contact 371, wire 375, wire 305, magnet 307, wire 309, and line wire 167. This energizes the second floor magnet and closes the switch 299 and holds the switch closed independently of the push button circuit. When the car starts and the bridge contact 365 leaves contact 371, the switch is held closed by the circuit which includes the second floor push button.

The circuit for energizing the third floor magnet 343 and closing the switch 335 independently of the push button circuit, is traced through line wire 141, wire 179, contact 359, switch 223, wire 361, bar 363, bridge contact 365, contact 373, wire 375, wire 341, magnet 343, wire 345, and line wire 167. This circuit energizes the magnet 343 and closes the switch 335 independently of the push button. When the car starts and the bridge contact 365 moves away from contact 373, the magnet is held energized and the switch is held closed by the circuit which includes the third floor push button.

When the switch 219 has been closed by the magnet 177 to decelerate and stop the car at the second floor, a circuit is completed which is traced through line wire 141, wire 179, wire 180, wire 249, contact 251, switch 221, wire 253, contact 255, wire 377, contact 379, bridge contact 193, bar 195, wire 197, magnet 177, wire 199, contact 201, switch 203, contact 205, wires 207, 209, 217 and 109, stop button 107 and line wire 105. Movement of bridge 115 contact 193 out of engagement with contact 379 interrupts this circuit, de-energizes the magnet 177, and allows the switch carrier 219 to open, thereby interrupting the circuits which bring the car to rest.

The circuit for the magnet 177 controlling deceleration of the car to the stop at the third floor is traced through line wire 141, wire 179, wire 180, wire 249, contact 251, switch 221, wire 253, wire 377, contact 381, bridge contact 193, bar 195, wire 197, magnet 177, wire 199, contact 201, switch 203, contact 205, wires 207, 209, 217 and 109, stop button 107 and line wire 105. When the bridge contact 193 moves away from contact 381, the circuit just described is interrupted, the magnet 177 is 120 de-energized, and the switch carrier 219 opens, thereby interrupting the circuits which bring the car to rest at the third floor.

When the down magnet 177 is energized, the switch carrier 219 is moved so as to throw the switch 113 out of engagement with the contact 115, thereby interrupting the circuit to the down direction magnet 103. This allows the switch 131 to open, thereby interrupting the main feed lines for causing down-travel of the car, and these circuits are now completed through the switches 225, 227, 229 and 231 on the carrier 219.

When the circuits are set for up-travel of the car, the down magnet 177 cannot be energized, since its circuits are broken by switch 203.

To enable the operator in the car to stop the down travelling car at any floor, push buttons 1, 2 and 3 are provided in the car. The circuit completed by pressing button 1 is traced through line 5 wire 141, wire 179, wire 383, wire 384, contact 385, push button 1, contact 387, wire 389, contact 391, bridge contact 193, bar 195, wire 197, magnet 177, wire 199, contact 201, switch 203, contact 205, wires 207, 209, 217 and 109, stop button 107 and 10 line wire 105.

Next will be described the circuit completed by pressing button 2 in the car to bring the down travelling car to a stop at the second floor. This circuit is traced through line wire 141, wire 179, 15 wire 383, wire 384, contact 393, push button 2, contact 395, wire 397, contact 399, bridge contact 193, bar 195, wire 197, magnet 177, wire 199, contact 201, switch 203, contact 205, wires 207, 209, 217 and 109, stop button 107, line wire 105.

20 The circuit completed by pressing button 3 to bring the down travelling car to rest at the third floor is traced through line wire 141, wire 179, wire 383, wire 384, contact 401, button 3, contact 403, wire 405, contact 407, bridge contact 193, bar 195, 25 wire 197, magnet 177, wire 199, contact 201, switch 203, contact 205, wires 207, 209, 217 and 109, stop button 107 and line wire 105.

Pressing any one of buttons 1, 2 and 3 in the car will complete a circuit which energizes the magnet 177 and causes deceleration of the car as 30 previously described. This circuit for said magnet is completed when the bridge contact 193 is in engagement with any one of the contacts 391, 399 and 407 and the car is in a stopping zone. The 35 engagement of the bridge contact 193 with any one of the contacts 391, 399 and 407 is momentary, and the engagement is interrupted before the car comes to a rest. The purpose of this is to energize the magnet 177 momentarily in order to close 40 the switch carrier 219. The circuit to the magnet 177 is completed independently of the engagement of the bridge contact 193 with contacts 391, 399 and 407 through the circuit including the switch 221 on carrier 219 as before described.

45 Assuming two cars are approaching a floor and one of these cars is to be stopped by the operator in the car to leave passengers, and the two cars are approaching a floor at a distance not greater than the distance between two floors, and assuming 50 that a passenger at the floor approached by the cars presses the button at that floor to stop a car, then due to the position of the contacts arranged for stopping the cars at that floor under the control of the operator, the car which has 55 no previous arrangement to stop at that floor will not take the call, but the call will be taken by the car which is to stop to leave passengers. This is accomplished by the arrangement of the contacts 391, 399, and 407. They are of such 60 length and so arranged that the bridge contact 193 will reach them and energize magnet 177 to bring in switch arm 219 sooner than it would be actuated by engagement of the bridge contact with contacts 171, 321 and 357 as initiated by 65 pressure on a floor button.

Now it will be assumed that the car is travelling up. The operator in the car presses an up-button 408 in the car to complete a circuit which energizes the up-magnet 409. This circuit is 70 traced through line wire 105, stop button 107, wire 109, button 408, wire 411, switch 413, contact 415, wire 417, contact 419, switch 421, contact 423, wire 425, up-magnet 409, wire 427, and line wire 129. Energization of the magnet 409 moves the 75 switch 429 into engagement with contacts 433,

435, 437, and 439. These contacts are in the circuits which are similar to those made by a three speed car switch of the usual system.

Since the up-button 408 is pressed momentarily, magnet 409 is made a holding magnet by 80 a shunt around said button including wires 217 and 440, contact 440a, switch 121, contact 440b and wire 440c leading to wire 411.

The circuit interrupted by pressing a button at the first floor for arresting up-travel of the 85 car at that floor, is traced through main line 141, wire 441, contact 445, push button 447, contact 449, wire 451, contact 453, switch 455, contact 457, wire 459, wire 461, magnet 463, wire 465, and main line 467. Breaking this circuit de-energizes the magnet 463 and allows the switch 455 to open under the influence of gravity.

A bridge contact carrier 469 (Fig. 5) is caused to travel with the car and is moved by the screw 95 81 referred to. The carrier 469 has a contact 473 thereon which is adapted to engage a contact 471 completing a circuit for the magnet 477 for up-travel of the car. The circuit for this magnet is traced through main line 141, wire 479, wire 481, contact 483, switch 485, contact 487, 100 wire 489, contact 471, contact 473 on carrier 469, wire 209a, contacts 49 and 50 at selector, wire 210a, switch E', wire 210b, wire 491, magnet 477, wire 493, contact 495, switch 497, contact 493, wires 501, 209, 217 and 109, stop button 107, and 105 line wire 105.

Magnet 477 is now energized, and it draws to it the switch carrier 503 which is provided with switches 505, 507, 509, 511, 513 and 515, all of said switches being insulated from one another. 110 The switches 509, 511, 513 and 515 are respectively brought into engagement with contacts 517, 519, 521 and 523, which have current standing thereon, through wires 541, 543, 545 and 547, which respectively lead to contacts 433, 435, 437 115 and 439, the latter contacts being adapted to be engaged by switch 429.

When the switch carrier 503 is moved by the up-magnet 477 as described, it draws switch 413 referred to out of engagement with contact 415, 120 and this breaks the circuit to the up-magnet 409. Now the car continues to travel up through the circuits which include switches 509, 511, 513 and 515, which are respectively in engagement with contacts 517, 519, 521 and 523. The circuit described for energizing the magnet 477 was momentarily completed by engagement of the contact 473 on carrier 469 with contact 471. At the end of this momentary condition the magnet 477 becomes a holding magnet through a circuit 125 which is traced through main line 141, wire 479, wire 549, contact 551, switch 505, wire 555, contact 557, bridge contact 558 on carrier 469, bar 475, wire 491, magnet 477, wire 493, contact 495, switch 497, contact 49, wires 501, 209, 217 and 109, stop button 107 and line wire 105.

Next will be described the means for causing deceleration of the up travelling car in coming to its stop. As the car comes to a stop the carrier 469 after causing contact 473 to leave contact 471, will bring a bridge contact 557 on carrier 469 into engagement with a set of three contacts 559, 561 and 563, and a bar 565, said contacts being of different lengths. These contacts are for the first floor. A set of contacts 567, 569 and 571 is 130 provided for the second floor, and a set of contacts 573, 575 and 577 is provided for the third floor. A set of such contacts will be provided for each floor, three sets being shown herein for purposes of illustration. The bridge contact 557 135

cooperates with all of these contacts and the bar 565.

The bar 565 is connected by wire 579 with switch 509. The contact 563 is connected by wire 581 with switch 511. The contact 561 is connected by wire 583 with switch 513. The contact 559 is connected by wire 585 with switch 515.

As the car approaches its stop, the bridge contact 557 on carrier 469 will be brought into engagement with contacts 559, 561 and 563, and will leave them in the order named. When bridge contact 557 leaves contact 559, it interrupts one of the circuits for the three speeds. When the bridge contact 557 leaves contact 561, it interrupts another of said circuits, and when the bridge contact 557 leaves contact 563, it interrupts the final circuit in the deceleration control, and the car is thus brought automatically gradually to rest at the floor.

Now will be described means to vary initiation of deceleration of the car to stop for up travel in response to variation in the speed of the car. To this end a pair of contacts 586a and 586b (Fig. 10) are provided adjacent the governor actuated contact 286h, referred to. A wire 586a tapped from wire 585 (Fig. 3) leads to contact 286h. The contact 586a is connected by a wire 588 and a branch wire 588a with contact 573a adjacent to contact 573 (Fig. 8). The contact 586b is connected by a wire 590 and a branch wire 590a with a contact 573b adjacent to contact 573a. Branch wires 586c and 586d tapped from wire 586a lead to contacts 559 and 567 respectively.

The construction is such that when the car is running as an express and is to make a stop, the governor 286 will hold the contact 286b away from contacts 586a and 586b thereby breaking the circuits including the contacts 573a and 573b and deceleration will be initiated when the bridge contact 557 leaves contact 573. When the car is running at a slower speed, the circuit including contact 573b will be broken, but the circuit including contact 573a will be closed, and deceleration will be initiated when the car is nearer the floor and when the bridge contact 557 leaves contact 573a. When the car is running at a still slower speed the circuits including both contacts 573a and 573b will be closed, and deceleration will be initiated when the car is still nearer the floor and when the bridge contact 557 leaves contact 573b.

In a similar manner for the other floors, variation in the initiation of deceleration in response to the speed of the car, will be accomplished.

While for purposes of illustration two contacts have been shown adjacent each of contacts 559, 567 and 573 in circuits controlled by the governor for varying the distance from the floor in initiating deceleration to stop, it will be understood that any number of such contacts in circuits controlled by the governor may be employed depending upon the high speed of the car.

Next will be described the circuit controlled by the button at the second floor for bringing the car travelling upward to a stop at that floor. This circuit includes wire 587 tapped from main line 141, contact 539, push button 591, contact 593, wire 595, contact 597, switch 599, contact 601, wire 603, wire 605, magnet 607, wire 609 and line wire 467.

Before the second floor button 591 is pressed, the magnet 607 is in energized condition, and the switch 599 is closed. When the button is pressed the circuit to the magnet is broken, and the switch 599 opens under the influence of gravity. This initiates the operations already described for bringing the car to a stop, and in this instance at

the second floor. The circuit for accomplishing this is traced through main wire 141, wire 479, wire 481, wire 600, contact 602, switch 604, contact 606, wire 608, contact 610, contact 473 on carrier 469, wire 209a, contacts 49 and 50 at the selector, wire 210a, switch E', wire 210b, wire 491, magnet 477, wire 493, contact 495, switch 497, contact 499, wires 501, 209, 217 and 109, stop button 107 and line wire 105.

Next will be described the circuit controlled by the button at the third floor for bringing the car to a stop at that floor. This circuit is traced through a wire 611, contact 613, push button 615, contact 617, wire 619, contact 621, switch 623, contact 625, wire 627, wire 629, magnet 631, wire 633, and line wire 467. Before the third floor push button is pressed, the circuit is completed and the magnet 631 is in energized condition and switch 623 is closed. When the button is pressed, the circuit is broken, the magnet is de-energized, and switch 623 opens under the influence of gravity. On opening switch 623, a circuit is completed which is traced through line wire 141, wire 479, wire 481, wire 635, contact 637, switch 639, contact 641, wire 643, contact 645, contact 473 on carrier 469, wire 209a, contacts 49 and 50 at the selector, wire 210a, switch E, wire 210b, wire 491, magnet 477, wire 493, contact 495, switch 497, contact 499, wires 501, 209, 217 and 109, stop button 107 and line wire 105.

Means is provided for completing the circuits for the floor magnets and energizing said magnets to close the switches which are opened by pressing floor buttons. This is done so that after a floor button has been pressed to bring the car to a stop, any additional pressing of floor buttons will not de-energize said magnets, and other cars in the bank will be prevented from responding to that call. Also, this means is to close the switches to be ready to stop cars for calls after the car has left the floor to which it was called. This means includes a circuit traced through line wire 141, wire 479, wire 647, contact 649, switch 597, wire 651, bar 653, bridge contact 655 on carrier 469, contact 657, wire 659, wire 461, magnet 463, wire 465 and line wire 467. When this circuit is completed by engagement of bridge contact 465 with bar 653 and contact 657, the magnet 463 is energized and the switch 455 is closed, thereby completing the circuit through the push button 447 as well as through the circuit just described, and the magnet 463 becomes a holding magnet. Starting of the car and movement of the bridge contact 655 away from contact 657 leaves the magnet in energized condition, but through the floor push button circuit only.

To energize the second floor magnet 607 independently of the push button circuit, and close switch 599, a circuit is provided traced through line wire 479, wire 647, contact 649, switch 597, wire 651, bar 653, bridge contact 655, contact 665, wire 667, wire 629, third floor magnet 631, wire 633, and main line 467. This completes the circuit through the push button 615 as well as through the circuit just described, so that the magnet 631 becomes a holding magnet. Starting of the car and movement of the bridge contact 655 away from contact 665 leaves the magnet 631 in energized condition, but through the floor push button circuit only.

When the switch carrier 503 has been moved by the magnet 477 to cause the switches carried thereby to engage the contacts adjacent thereto, and the car is to decelerate and stop at the second floor, a circuit is completed which is traced through main line 141, wire 479, wire 549, con-

tact 551, switch 505, wire 555, wire 669, contact 671, bridge contact 558, bar 475, wire 491, magnet 477, wire 493, contact 495, switch 497, contact 499, wires 501, 209, 217 and 109, stop button 107 and line wire 105. Movement of bridge contact 558 out of engagement with contact 671 interrupts this circuit, de-energizes the magnet 477, and allows the switch carrier 503 to open under the influence of gravity, thereby interrupting the 10 circuits and bringing the car to rest at the second floor.

The circuit for the magnet 477 controlling the deceleration of the car to stop at the third floor, is traced through line wire 141, wire 479, wire 15 549, contact 551, switch 505, wire 555, wire 669, contact 673, bridge contact 558, bar 475, wire 491, magnet 477, wire 493, contact 495, switch 497, contact 499, wires 501, 209, 217 and 109, stop button 107, and line wire 105. Movement of 20 bridge contact 558 out of engagement with contact 673 interrupts this circuit, de-energizes the magnet 477, and allows the switch carrier 503 to open under the influence of gravity, thereby interrupting the circuits and bringing the car to 25 rest at the third floor.

When the magnet 477 is energized, switch carrier 503 is moved so as to throw the switch 413 out of engagement with the contact 415, thereby interrupting the circuit to the up-magnet 409. 30 This allows switch 131 to open, thereby interrupting the main feed lines for causing up-travel of the car, and these circuits are now completed through the switches 509, 511, 513 and 515 on the switch carrier 503. When the circuits are set for 35 down-travel of the car the magnet 477 cannot be energized, since its circuits are broken by switch 497.

To enable the operator in the car to stop at any floor with the car travelling upward, push 40 buttons 1', 2' and 3' are provided in the car. The circuit completed by pressing button 1' is traced through line wire 141, wire 179, wire 383, wire 675, contact 677, push button 1', contact 679, wire 681, contact 683, bridge contact 558 on carrier 469, bar 475, wire 491, magnet 477, wire 493, contact 495, switch 497, contact 499, wires 501, 209, 217 and 109, stop button 107, and line wire 105.

The circuit completed by pressing button 2' in 50 the car to bring the car to a stop at the second floor is traced through line wire 141, wire 179, wire 383, wire 675, wire 685, contact 687, push button 2', contact 689, wire 691, contact 693, bridge contact 558 on carrier 469, bar 475, wire 491, magnet 477, wire 493, contact 495, switch 497, contact 499, wires 501, 209, 217 and 109, stop button 107, and line wire 105.

The circuit completed by pressing button 3' to arrest an up-travel car at the third floor, is traced 55 through main line 141, wire 179, wire 383, wire 675, wire 695, contact 697, push button 3', contact 699, wire 701, contact 703, bridge contact 558 on carrier 469, bar 475, wire 491, magnet 477, wire 493, contact 495, switch 497, contact 499, wires 501, 209, 217 and 109, stop button 107, and line wire 105.

Pressing any one of buttons 1', 2', 3' in the car will complete a circuit which energizes the up-magnet 477 and causes deceleration of the 70 car to its stop as previously described. This circuit is completed when the bridge contact 558 is in engagement with any one of the contacts 683, 693, and 703, and this occurs when the car is in a stopping zone. The engagement of the bridge 75 contact 558 with any one of contacts 683, 693, and

703 is momentary, and the engagement is interrupted before the car comes to a rest. The purpose of this is to energize the magnet 477 momentarily in order to close the switch carrier 80 503. Then the circuit to the decelerating magnet 477 is completed independently of the bridge contact 473.

Assuming two cars are approaching a floor, and one is to be stopped by the operator in the car to leave passengers, and the two cars are approaching a floor at a distance not greater than the distance between two floors, and assuming a passenger at the floor approached by the cars presses the button at that floor to stop a car, then the car which is to be stopped to leave passengers will take the call, and the car which otherwise would stop at that floor due to the call from said floor, will not take the call. This is accomplished by making the contacts 683, 693 and 703 of a length and giving them a location such that the decelerating magnet 477 will be energized and the carrier 503 shifted to bring its switches in engagement with the contacts adjacent thereto previously to completion of the circuit controlled by a push button at a floor.

The push buttons in each car are so constructed and arranged that the operator of the car can press all of the buttons for floors where stops are to be made, and the car will automatically travel to and make the stops in proper sequence.

Referring to Fig. 4a, three push buttons for up-travel stops and three push buttons for down-travel stops are shown. These buttons are on slides 801 mounted in sleeves 803 on plates 805 and have stop collars 807 urged by coil springs 809 into engagement with ends of the sleeves. At the inner ends of the slides are heads 811 adapted to be caught by hooks 813 secured to bars 815 having slots 817 slidable on pins 819. There is slight play of the slides in the sleeves so that the heads may be pressed by springs 820 up toward the hooks. These bars 815 are urged downward by coil springs 821. Up and down direction buttons are provided on slides 823 having cams 825 for engagement with pins 827 on the upper ends of the bars.

The construction is such that the car operator can at the start press all of the buttons for floors where stops are to be made, and the buttons will be held in by engagement of the hooks with the heads of the button slides. This will pre-set the system so that the car will make the stops in sequence and without further attention to stops on the part of the operator, and without waste of time. When the car has completed its trip the operator presses one of the direction buttons which causes its cam to lift the hook carrying bar, thereby releasing the hooks from the button slides and allowing their springs to shift them outward to be in readiness again to be pressed.

When the car is to be run as an express, the operator can open the switches E and E' in the 135 circuits for the down and up magnets 177 and 477, thereby cutting out stopping of the car by pressure of the buttons at floors.

When the car is fully loaded the weighing machine will have turned the selector rotor sufficiently to cause its pin 54 to strike the lever 25 and separate contacts 49 and 50 and separate contacts 51 and 52, thereby breaking the circuits of the down and up magnets 177 and 477, and 145 preventing response of the car to calls for stops from buttons at floors.

Economic, efficient operation of a bank of elevator cars requires merely one car of the bank to respond to a call to stop at a floor, and this car 150

should be the one nearest that floor, provided it is not too near to initiate deceleration to the floor. Accordingly the electric connections should be such that pressing one button at a floor shall summon to stop the nearest available up-travelling car of the bank, and pressing another button at that floor shall summon to stop the nearest available down-travelling car of the bank.

For purposes of illustration, three floors are considered and diagrammatically in Fig. 11 are shown up and down push buttons at three floors connected in the usual manner to the master magnet floor board 829 from which cables 831 and 833 and branch wires 835 and 837 lead to the boards 68 for the three elevators. For down-travel cars these wires are connected to contacts corresponding to contacts 171, 321 and 357, and for up-travel cars said wires are connected to contacts corresponding to contacts 471, 610 and 645 of the system presented in Figs. 8, 9 and 10, and to make this more clear there is shown a wire 191a leading from wire 191 to contact 171', a wire 319a leading from wire 319 to contact 321', and a wire 355a leading from wire 355 to contact 357', said contacts being in the control system for another car of the bank than that car to which the system of Figs. 8, 9 and 10 appertains. These contacts are for down-travel of the car. Similarly for up-travel of the car, there are shown a wire 489a leading from wire 489 to contact 671', a wire 608a leading from wire 608 to contact 610', and a wire 643a leading from wire 643 to contact 645'.

As stated, deceleration of the car to a stop should commence at a greater distance from the floor when the car is running as an express or at full speed, than when the car has not had time to build up to full speed. This regulation is accomplished by the governor 286 and the circuits controlled thereby.

Also, as stated, deceleration of the car to a stop should commence at a greater distance from the floor with resultant heavier loads than with lighter loads. This regulation is accomplished by the weighing machine, the selector and the electric motor control which adjusts the panel 67 (Fig. 5) carrying the decelerating control contacts.

It will be understood that the invention is not limited to the specific embodiment shown, and that various deviations may be made therefrom without departing from the spirit and scope of the appended claims.

What is claimed is:

1. In an elevator system, the combination of a car, an electric motor for driving the car, means on the car for weighing the load thereon, a plurality of floors, and means for reducing the speed of the car in approaching each floor including different motor speed circuits having contacts, a bridge contact carrier moved by travel of the car to and past said contacts to make and progressively interrupt said circuits, and means controlled by the weighing means to adjust said contacts in the path of the carrier and in response to variations in the car load, thereby to initiate deceleration of the car at varying distances from the floor.

2. In an elevator system, the combination of a car, an electric motor for driving the car, means on the car for weighing the load thereon, a plurality of floors, a panel having sets of contacts thereon including a set for each floor for up-travel and a set for each floor for down-travel, each of said sets having graded contacts, a pair

of bridge contact carriers, means actuated by travel of the car for moving one of the carriers past the up-travel contact sets and for moving the other carrier past the down-travel contact sets, different motor speed circuits including said contact sets, and means controlled by the weighing means automatically to increase or decrease the distance of approach of the carriers to said sets according to increase or decrease in the car load.

3. In an elevator system, the combination of a car, an electric motor for driving the car, means on the car for weighing the load thereon, a plurality of floors, and a control system for stopping the car at the floors comprising up and down magnets, circuits for said magnets, floor magnets, normally closed circuits for said floor magnets including push button switches at the floors, switches in the up and down magnet circuits closed on interruption of the push button magnet circuits thereby to set the up and down magnet circuits in readiness to be completed, carriers moved by travel of the car and having contacts thereon for completing the circuits of the up and down magnets on approach of the car to a floor, arms having switches thereon, different speed circuits including contacts engaged by said switches, sets of graded contacts for each floor and in said different speed circuits, and bridge contacts on the carrier adapted to pass and progressively leave the contacts of a set thereby to decelerate the speed of the car to a stop at the floor.

4. In a floor push button control for stopping an elevator car at floors, the combination of push buttons at the floors, floor magnets, circuits for the floor magnets including said buttons, up and down magnets, circuits for the up and down magnets including switches closed on de-energization of the floor magnets, carriers moved by travel of the car and having contacts for momentarily completing the up and down magnet circuits, arms having switches thereon, holding circuits for the up and down magnets including switches on the arms and bridge contacts on the carriers, circuits for the floor magnets including switches on the carriers, arms actuated by the up and down magnets, different speed circuits including series of fixed contacts, switches on the arms to engage said fixed contacts, sets of graded contacts for the floors, and bridge contacts on the carriers adapted to pass and progressively leave the contacts of the sets, thereby to progressively break the speed circuits and cause the car to decelerate to a stop.

5. An elevator system comprising a plurality of floors, a car, and a push button control system including up and down push buttons at the floors, floor magnets in circuit with the push buttons, switches operated by the floor magnets; a machine comprising up and down magnets, arms actuated by said magnets, switches on said arms in circuits for different speeds of the elevator, up and down sets of decelerating contacts for each floor in circuit with said switches, up and down contact carriers moved by the elevator car past said sets of contacts to cause deceleration of the car to the floors; and circuits for said up and down magnets including the switches actuated by said floor magnets and including contacts engaged by contacts on the carriers as the car approaches a floor.

6. In a control system for an electric elevator, the combination of the elevator car, a plurality of floors, push buttons at the floors, means for

weighing the car load, means operable in response to pressure of a floor button to cause the car to stop at that floor, said means including floor magnets, circuits for said magnets including the push buttons, up and down magnets, circuits for said up and down magnets including switches closed on de-energization of floor magnets, and switches in the up and down magnet circuits automatically opened by the weighing means if the car is fully loaded, thereby to prevent the car from responding to a call by a floor push button.

7. In a control system for an electric elevator, the combination of the elevator car, a plurality of floors, push buttons at the floors, a machine on the car for weighing the car load, means operable in response to pressure of a floor button for causing the car to stop at said floor, said means including up and down magnets and their circuits, decelerating circuits including switches operated by said magnets, means actuated by travel of the car for rendering said decelerating circuits effective to stop the car, and means automatically operated by the weighing means to interrupt the up and down magnet circuits if the car is fully loaded, thereby to prevent the car from responding to a call to a floor.

8. In an electric elevator system control, the

combination of the elevator car, an electric motor for driving the car, different speed circuits for the motor including sets of graded contacts for floors, carriers moved by travel of the car, one for up-travel and the other for down-travel of the car, bridge contacts on the carriers adapted to pass and progressively leave contacts of the sets thereby to cause steps of deceleration of the car to stop, each of said sets having a plurality of contacts in alinement for the initial step, a governor driven by travel of the car, and circuits including some of the aligned contacts and interrupted by the governor when the car is travelling at high speed.

9. In combination, an elevator car, a hoisting motor having multi-speed regulation, slow down means having electro-responsive means to actuate same, control means for each of a plurality of landings, circuits responsive to said control means to energize said electro-responsive means to cause automatic slow down, a contactor in each of said circuits, an additional contactor common to all of said contactors, movable by the car successively to engage said contactors to complete said circuits, and a circuit to maintain said electro-responsive means energized independently of said first named circuits.
